UNITED STATES PATENT OFFICE.

CHARLES FISHER, OF CHICAGO, ILLINOIS, ASSIGNOR TO THE AUTOMATIC RECORDING
SAFE COMPANY, OF CHICAGO, ILLINOIS, A CORPORATION OF ILLINOIS.

DESIGN FOR A CLOCK-BANK CASE.

55,853.

Specification for Design.

Patented July 20, 1920.

Application filed February 27, 1917. Serial No. 151,355. Term of patent 7 years.

To all whom it may concern:

Be it known that I, CHARLES FISHER, a citizen of the United States, residing at Chicago, in the county of Cook and State of Illinois, have invented a new, original, and ornamental Design for a Clock-Bank Case, of which the following is a specification, reference being had to the accompanying drawing, forming a part hereof.

The figure is a perspective view of a clock-bank case in accordance with my new design.

I claim:

The ornamental design for a clock-bank case, as shown.

CHARLES FISHER.
